Patented Mar. 19, 1918.

UNITED STATES PATENT OFFICE.

HENRY G. SAAL, OF CHICAGO, ILLINOIS.

MOP.

1,259,780.

Specification of Letters Patent. Patented Mar. 19, 1918.

Application filed October 2, 1915. Serial No. 53,723.

To all whom it may concern:

Be it known that I, HENRY G. SAAL, a citizen of the United States, residing at Chicago, in the county of Cook and State of Illinois, have invented a certain new and useful Improvement in Mops, of which the following is a full, clear, concise, and exact description, reference being had to the accompanying drawings, forming a part of this specification.

My invention relates to mops, a mop constructed in accordance with the invention including a handle which is angularly adjustable with respect to the mop and an improved construction of the mop head whereby oil or other liquid that the mop is to apply may readily be supplied to the strands of the mop. While I prefer to employ both these characteristics in the same construction I do not wish to be limited to such an arrangement. The handle is made adjustable by having included in its structure a short or stub shaft with which a remaining portion of the handle is in threaded connection, this shaft being placed within a bearing carried by the mop head, a threaded part of the handle projecting through a slot in the bearing into engagement with the shaft whereby a shoulder portion of the handle is tightly engaged with the bearing for the shaft. When the handle is to be readjusted its gripping portion is unscrewed sufficiently to release it from engagement with the bearing whereby the new adjustment may be selected and secured. A clamping washer desirably surrounds the threaded portion of the handle to engage the bearing and the shoulder part of the handle directly whereby the area of frictional contact that holds the selected adjustment of the handle is increased.

The mop head is desirably of dished formation with holes in the bottom of the dish structure. This arrangement permits a quantity of oil or other liquid to be poured in the hollow of the dish, this liquid finding its way through openings that are provided in the bottom of the dish and which openings serve to direct the liquid into the strands of the mop.

I will explain my invention more fully by reference to the accompanying drawing showing the preferred embodiment thereof and in which—

Figure 1 is a view in elevation of the mop with a part of the handle removed, one

alternative position of the handle being shown in dotted lines; Fig. 2 is a plan view of the structure illustrated in Fig. 1 with the handle shown in the position indicated by dotted lines in Fig. 1; Fig. 3 is a view on line 3 3 of Fig. 2; Fig. 4 is a sectional view taken at right angles to the direction in which Fig. 3 is taken; and Fig. 5 illustrates a detail of construction.

Like parts are indicated by similar characters of reference throughout the different figures.

The mop strands 1 are clamped between a clamping ring 2 and the peripheral part 70 of a dished head plate 3, screws 4 serving to bind the clamping members 2 and 3 into tight engagement with the strands 1. The strands desirably completely surround the ring 2 so as to be within the bore of such ring as well as upon its exterior. The plate 3 of the mop head is dished to afford a space in which oil or other liquid may be poured upon the mop head without flowing over the periphery thereof. The bottom of 80 the dish is provided with openings 5 through which the liquid may find downward passage on to the strands of the mop, an arrangement that facilitates the application of liquid to the mop strands when 85 the mop is to be employed in applying such liquid to surfaces. This arrangement is of particular use when the mop is to be employed to polish floors, the polishing oil or liquid being quickly and economically applied to the mop.

It will be noted that by dishing the plate 3 and providing the ring 2 the intense clamping action upon the strands will occur between the inner edge of the ring and 95 the outer portion of the dish and as the openings 5 are located inwardly of the inner edge of the ring 2 the oil passing therethrough will only feed freely to those strands located inwardly of the ring 2 and 100 during the working of the mop this oil will be worked uniformly into the strands which lie outwardly of the ring 2. Through the instrumentality of this structure it will be obvious that I am enabled to prevent excessive feed of the oil throughout the entire mop in that I utilize the inner strands themselves as a means for positively transmitting the oil to the outer strands.

The metal plate 3 desirably supports a 110 circular bearing 6 in which there is supported a short or stub shaft 7 which, in ef-

fect, constitutes a part of the handle structure inasmuch as it is connected with the gripping portion 8 of the handle by means of a screw 9 that is in fixed relation with the gripping portion. The bearing 6 has a slot 10 formed therein that is parallel with the plane of the bearing and is included in the plane of swinging movement of the screw 9. When it is desired to readjust 10 the position of the handle the gripping part thereof is turned so as to unscrew the screw 9, whereupon the handle may be swung to the desired position, the screw 9 working within the slot 10. After the new position 15 has been selected the screw 9 is screwed inwardly to clamp the shaft 7, the screw 9, and the gripping portion 8 of the handle in firm relation. The engagement of the 20 portions 7 and 8 of the handle with the bearing 6 may be enhanced by providing the friction washer 11 between the ferrule 12 at the lower end of the handle and the bearing 6.

While I have herein shown and particu-

larly described the preferred embodiment 25 of my invention I do not wish to be limited to the precise details of construction shown as changes may readily be made without departing from the spirit of my invention, but having thus described my invention I 30 claim as new and desire to secure by Letters Patent the following:—

A mop comprising a head plate having a central dish portion provided with openings in its bottom, a clamping ring disposed beneath the head plate with its inner edge located within the limits of the dish portion and outwardly of said openings, mop strands confined between the head plate and clamping ring, and clamping bolts connecting said plate and ring. 35

In witness whereof, I hereunto subscribe my name this twenty-ninth day of June, A. D. 1915.

HENRY G. SAAL.
